UNITED STATES PATENT OFFICE

GUSTAV SCHÖNGUT, OF VIENNA, AUSTRIA

PUMP FOR LIQUIDS

Application filed July 26, 1929, Serial No. 381,282, and in Austria July 27, 1928.

This invention relates to improvements in pumps for liquids and the like, of the kind in which electro-magnetic force is brought to bear directly on the pump-piston itself.

5 In previous embodiments of this principle the pump-piston is so constructed as to represent the armature of a magnet, and this armature at the same time operates the cut-out control. Since the armature (serving as 10 piston) must necessarily be packed to prevent leakage, the greater part of the energy applied is wasted in overcoming friction. And the fact that the cut-out control is operated by the piston itself implies complicated and sensitive mechanism.

15 A further known type of pump made in accordance with this principle is one in which the armature and the piston, through separate and distinct elements in the construction, are 20 coupled together by means of a spring. The disadvantage of this type of construction is that it does not sufficiently exploit the magnetic force employed.

The object of the present invention is to 25 provide a pump with direct electro-magnetic piston-drive which is simpler and cheaper to construct than the types hitherto produced and which avoids the disadvantages of the latter. According to the invention the pump-piston is perfectly-independent of the armature of the magnet and is driven by the blows resulting from the to-and-fro motion of the armature. To this end the armature is provided with a certain interval of free play at 30 the beginning of each stroke, during which it is given time to gather impetus which is then transmitted to the piston at the moment of striking.

The armature is movably mounted either 35 in the coils of a solenoid or between two horse-shoe magnets. The interruption of the current for the coils of the solenoid or for the windings of the horse-shoe magnets is effected by an interrupter or reversing device 40 which is separate from and has no mechanical connection whatever with the pump itself. The interrupter used may be one of any of the known types, such as the mechanical, electrolytic, or discharge-tube rectifier type. 45 The separation of the controlling mechanism

from the pump itself enables the latter to be inserted in the liquid to be pumped,—a consideration of great practical value.

The drawings illustrate in vertical section in Figs. 1 and 2 two examples of pumps made 55 in accordance with the invention.

In the embodiment illustrated in Fig. 1 two solenoid coils *b*, *c* are mounted on a tubular holder *a*. The middle pieces *a*₁ of this holder consist of magnetically non-conductive material. The coils *b*, *c* are enclosed in a liquid-tight casing *m*. Within the tubular holder *a* the armature *d* is so fitted as to be freely movable to and fro in a vertical sense. The stroke of the armature *d* is limited by a pin *p* 60 in the holder *a* which projects into a groove *r* of the armature *d*. The lower end of the tubular holder *a* forms the suction piece *n* of the pump, and is provided with the suction valve 1. 65

The pump-piston *i* is provided with an extension piece *x*, which projects through a bore *f* in the armature *d* and is itself provided with an axial bore *j*. The upper end of the member *x* is fitted with the pressure valve *g*, above 70 which a nonreturn valve *h* can also be provided. The nozzle *o* serves for the connection of the pressure pipe.

The pump-piston *i*, or its extension piece *x* is provided with a stop-ring *s*, which allows 75 of a certain play of the armature *d* to and fro in a socket *t*. When the coil *c* is switched in (in the position shown in Fig. 1) the armature *d* will be drawn downwards, first travelling free for a distance determined by the length 80 of the socket *t*, whereupon the stop-ring *s* strikes the end of the socket *t*, so that the member *x* and the pump-piston *i* are operated by the blow. The procedure is the same 85 when the coil *b* is switched in, and the armature travels upwards.

The form of construction illustrated in Fig. 2 differs from that of Fig. 1 only in that two horse-shoe magnets *v*, *v*₁ serve to drive the armature. The armature *d*₁ is fitted in 90 the ordinary manner between the two horse-shoe magnets *v*, *v*₁ and combined with the tubular tappet *d*.

What I claim is:

1. A liquid pump including an electro- 100

magnet and an armature actuated thereby, a pump piston actuated by said armature, and means permitting limited movement of the armature relative to the piston.

5 2. A liquid pump including an electromagnet and an armature actuated thereby, a pump piston actuated by said armature, and means permitting limited movement of the armature relative to the piston whereby
10 the range of movement of the armature is greater than the piston.

3. A liquid pump including an electromagnet and an armature actuated thereby, a pump piston actuated by said armature, and
15 means permitting limited movement of the armature relative to the piston whereby the range of movement of the armature is greater than the piston, and upon reversal of movement of the armature a blow is delivered
20 on the pump piston.

4. A liquid pump including an electromagnet and an armature actuated thereby, a valved pump piston actuated by said armature, and means permitting limited movement of the armature relative to the piston.

5. A liquid pump including an electromagnet having an axial bore, a pump piston movable in said bore, said magnet including an armature actuating the piston, and means
30 permitting limited movement of the armature relative to the piston.

6. A liquid pump including an electromagnet having an axial bore, a pump piston movable in said bore, said magnet including
35 an armature actuating the piston, and means permitting limited movement of the armature relative to the piston, said piston and armature being arranged telescopically one within the other.

40 7. A liquid pump including an electro-magnet having an axial bore, a pump piston movable in said bore, said magnet including an armature actuating the piston, and means permitting limited movement of the armature relative to the piston, said armature extending externally of said bore.

In testimony whereof I affix my signature.
GUSTAV SCHÖNGUT.
